PIPE HANDLING APPARATUS

Carl W. Pool, Wilmington, Calif.

Application September 24, 1946, Serial No. 699,012

3 Claims. (Cl. 214—1)

1

My invention relates to pipe handling apparatus.

An important object of the invention is to provide means for handling oil well pipe or casing when running the same into or pulling it out of an oil well.

A further object is to provide apparatus for handling pipe which will save time and labor, and avoid damage to the pipe.

A further object is to provide pipe handling apparatus of the type including a track and cars, in which the cars may be spotted or placed at any desired position on the track, locked in position for loading pipe onto the cars, and then unlocked and tilted for rolling or unloading the pipe from the cars.

A still further object is to provide apparatus of the above-mentioned class, which is particularly designed for use in oil fields, or in connection with wells, although capable of general use, and which is simple, durable and substantially trouble proof.

Other objects and advantages of the invention will be apparent during the course of the following description.

In the accompanying drawings, forming a part of this application, and in which like numerals are employed to designate like parts throughout the same,

Figure 1 is a side elevation of the pipe handling apparatus embodying my invention, parts broken away, and showing the same associated with a conventional oil well derrick.

Figure 2 is a plan view of the apparatus, parts broken away.

Figure 3 is an enlarged vertical transverse section taken on line 3—3 of Figure 1, parts omitted.

Figure 4 is a greatly enlarged vertical transverse section taken on line 4—4 of Figure 1.

Figure 5 is a fragmentary vertical longitudinal section taken on line 5—5 of Figure 4, and.

Figure 6 is a fragmentary vertical section taken on line 6—6 of Figure 4.

In the drawings, where for the purpose of illustration, is shown a preferred embodiment of my invention, the numeral 10 designates a standard gin pole or derrick, for use in running pipe 11 into, or pulling the same out of an oil well 12, or the like.

In the pipe handling apparatus proper, wherein my invention resides, the numeral 13 designates an elongated relatively stationary base, which is in the general form of an inverted T in transverse cross section. The base 13 has a lower flat horizontal base plate 14, and a vertically upstanding web or support plate 15, having longitudinally spaced vertical knuckles 16. The knuckles 16 have longitudinally aligned openings 17 for receiving a hinge rod 18.

Mounted upon the vertical web 15, and extending longitudinally of the base 13, for substantially

2

the full length of the same, is an elongated horizontal track section 19, including an upper horizontal web or plate 20, having depending longitudinally spaced vertical knuckles 21, adapted for interfitting with the knuckles 16, and being provided with longitudinally aligned openings 22, which register with the openings 17 in assembly and also receive the hinge rod 18. The track section 19 further comprises vertically depending side webs or guides 23, rigidly secured to the lower ends of which are inwardly extending longitudinal support rails or tracks 24.

Arranged to move longitudinally on the rails or tracks 24, and supported by the rails, are separate identical pipe supporting carriages 25. Each carriage 25 includes a flat horizontal top section 26, having transversely spaced pairs of longitudinally aligned vertically upstanding end extensions or supports 27, having journal openings 28, which in each pair, are in longitudinal alignment. The journal openings 28 receive end shaft extensions 29 of spaced parallel pipe rolls 30 in free rotational engagement. Each carriage 25 further includes vertical sides 31, carrying horizontal inwardly extending bottom sections 32, having vertically upstanding roller supports 33, having journal openings 34. Rotatably mounted within the openings 34, are shaft extensions 35 of carriage rollers or wheels 36, which are adapted for rolling on the upper surfaces of the rails 24.

Arranged adjacent to one end of the base 13, are transversely spaced vertically upstanding drum supports 37, carrying horizontal rotatable drums or spools 38, being preferably provided with crank handles 39, for rotating the drums or spools. Engaging over the rotatable spools 38, and arranged within suitable guide grooves formed on the peripheries of the spools, are suitable flexible cables 40, or the like. The arrangement of the cables 40 on the spools 38 is such, that when each spool is rotated, one end or run of its associated cable is wound upon the spool, while the other end or run is unwound from the spool.

One end of each cable 40 is rigidly attached near one end of each carriage 25, by means of a suitable clamp block 41, or the like, mounted upon the inner surface of one of the roller supports 33. The opposite end of each cable 40 is rigidly attached near the opposite end of each carriage 25, by means of another of the clamp blocks 41, mounted upon the roller support 33 which is spaced longitudinally from the first named roller support on that carriage. The cables 40 pass about pulley wheels 42, arranged adjacent to the opposite end of the base 13, and spaced transversely from each other, and rotatably mounted within the forked or yoke ends 43 of horizontal rods 44, carrying nuts 45. The rods 44 carry

suitable heavy coil compression springs 46, one of the ends of which are seated against the nuts 45, and the opposite ends of which are seated against the outer vertical surfaces of vertically upstanding stationary or fixed supports 47. The rods 44 are adapted for reciprocation within openings near the upper ends of the fixed supports 47, and the rods are positioned under the influence of the springs 46, which maintain the cables 40 taut, and which also absorb the shock of sudden starts and stops by the carriages 25.

Removable blocks or stops 48, or the like, may be arranged between the lower surfaces of the rails 24, and the top surface of the base plate 14, to prevent the tilting of the track section 19. These blocks 48 are shown in place in Figures 1 and 3 of the drawings, and arranged at the ends of the base plate 14, so as not to interfere with the longitudinal movement of the carriages 25.

It should be noted that the arrangement of the cables 40 is such, that the same are substantially enclosed by the track section 19 at all times, and this lessens the probability of the cables being fouled or causing any trouble. Also, the carriage rollers or wheels 36 are substantially enclosed within the track section 19, and mud, ice, and the like, do not tend to hamper the free rolling of the wheels.

The operation and use of the pipe handling apparatus is as follows:

Pipe or casing sections 11 are pulled from the oil well by the derrick 10. These pipe sections are heavy and would be difficult to handle, manually.

The carriages 25 are spotted or positioned at any desired point along the track section 19, by means of the crank handles 39, or by suitable automatic means. As illustrated in Figure 1, one end of the pipe being handled is placed between the pipe rolls 30 of one carriage 25. The friction and weight of the drum or spool 38 which is associated with that carriage is so little, as is the friction in the rollers 36 of that carriage, that the weight of the pipe being handled causes the carriage 25 to roll automatically to the position shown in dotted lines, in Figure 1, where the pipe may be rested horizontally, on the rolls 30 of both carriages 25 of the apparatus.

When it is desired to lift pipe sections from the pipe handling apparatus, as when running the pipe sections into the well, the carriage 25 which supports the lower end of the pipe being lifted will roll automatically to a position such as that shown in full lines in Figure 1.

During such operation of the handling apparatus, as has been described, the blocks 48 should be in place, to prevent the track section 19 from being tilted about the hinge rod 18. However, when it is desired to dump or roll the pipe being handled from its horizontal position upon the rolls 30 of both carriages 25, and onto the ground or a flat car, or the like, the track section 19 may be tilted, by any suitable means to a position illustrated in dotted lines in Figure 3, where the pipe being handled will roll off of the rolls 30, and be dumped.

The apparatus above described is not limited to use in connection with oil wells, but is obviously capable of general use for handling pipe.

It is to be understood that the form of my invention, herewith shown and described is to be taken as a preferred example of the same, and that various changes in the shape, size and arrangement of parts, may be resorted to, without

departing from the spirit of my invention, or the scope of the subjoined claims.

Having thus described my invention, what I claim is:

1. Pipe handling apparatus, comprising a base, including a base plate and a support web, a track section pivotally mounted upon the support web and adapted to tilt laterally of the same and including an upper plate, side webs secured to the upper plate, lower inwardly extending rails secured to the side webs, carriages mounted upon the track section and including top sections, depending sides secured to the top sections, bottom sections secured to the depending sides and extending inwardly from the same, upstanding roller supports secured to the bottom sections, rollers carried by the roller supports for rolling upon the rails, the arrangement being such that the rollers are substantially enclosed by said upper plate said side webs and said rails, spaced rolls mounted upon the top sections, flexible cables having ends attached near the opposite ends of the carriages, rotatable spools arranged adjacent to the track section and adapted for simultaneously winding and unwinding the opposite ends of the cables for moving the carriages separately longitudinally in either direction along the track section, the arrangement being such that the cables are substantially enclosed by said upper plate and said side webs.

2. Pipe handling apparatus, comprising a base including a base plate and a support web, a track section pivotally mounted upon the support web and adapted to tilt laterally of the same and including an upper plate, side webs, and rails, carriages mounted upon the track section and including top sections, sides secured to the top sections, bottom sections secured to the sides, roller supports secured to the bottom sections, rollers carried by the roller supports for rolling upon the rails, the arrangement being such that the rollers are substantially enclosed by said upper plate, said side webs and said rails, spaced rolls mounted upon the top sections and adapted for supporting pipe and means including flexible cables and rotatable spools for moving the carriages separately in either direction longitudinally along the rails.

3. In pipe handling apparatus, a base, a track section pivotally mounted upon the base and adapted to tilt laterally and including an upper plate, side webs and rails, pipe supporting carriages mounted upon the track section and including top sections, sides secured to the top sections, bottom sections secured to the sides, roller supports secured to the bottom sections, rollers carried by the roller supports for rolling upon the rails, the arrangement being such that the rollers are substantially inclosed by said upper plate said side webs and said rails, and means to move the carriages separately in either direction longitudinally of the rails.
